Primary Examiner—Cathron Brooks*Assistant Examiner*—Susan Moon Lee(74) *Attorney, Agent, or Firm*—Moore & Hansen, PLLP(57) **CLAIM**

I claim the ornamental design for a stock prod handle and base, as shown and described.

DESCRIPTION

FIG. 1 is a perspective view of a first embodiment of a stock prod handle and base showing my new design;

FIG. 2 is a left side elevational view thereof;

FIG. 3 is a front elevational view thereof;

FIG. 4 is a top plan view thereof;

FIG. 5 is a bottom plan view thereof;

FIG. 6 is a rear elevational view thereof;

FIG. 7 is a perspective view of a second embodiment of a stock prod handle and base shown with a handgrip;

FIG. 8 is a left side elevational view thereof;

FIG. 9 is a front elevational view thereof;

FIG. 10 is a top plan view thereof;

FIG. 11 is a bottom plan view thereof; and,

FIG. 12 is a rear elevational view thereof.

Portions shown in broken line are for illustrative purposes only and form no part of the claimed design.
